UNITED STATES PATENT OFFICE.

ROLLO F. WALTERS, OF DETROIT, MICHIGAN, ASSIGNOR TO CARR FASTENER COMPANY, OF CAMBRIDGE, MASSACHUSETTS, A CORPORATION OF MAINE.

SEPARABLE FASTENER.

Original application filed July 24, 1924, Serial No. 727,960. Divided and this application filed February 26, 1925. Serial No. 11,704.

This invention aims to provide an improved separable fastener particularly, though not exclusively, useful in connection with upholstery installations.

5 The application is a division of my prior application, Serial No. 727,960, filed July 24, 1924.

Reference is also made to a division of this application, Serial No. 281,181, filed 10 May 28, 1928.

In the drawings, which illustrate preferred embodiments of my invention:—

Figure 1 is an elevation view of a door of an automobile showing the frame and the 15 stud-receiving apertures therein;

Fig. 2 is an elevation view of the backing of an upholstered part, showing the studs secured thereto;

Fig. 3 is a section through the door frame 20 and upholstered part, showing the stud partly in elevation;

Fig. 4 is a fragmentary view of a portion of the upholstered part as viewed from that side thereof at which the stud heads are presented;

Fig. 5 is an elevation view of the preferred form of shiftable stud;

Fig. 6 is an enlarged section on the line 6—6 of Fig. 4;

30 Fig. 7 is a section similar to that shown in Fig. 6, showing a modified form of stud unit secured to the upholstered part;

Fig. 8 is an elevation of the modified form of stud unit; and

35 Fig. 9 is an elevation of the modified form of stud unit, as viewed from the opposite side from that shown in Fig. 8.

Referring to the form of my invention, as illustrated in Figs. 1 through 6, I have 40 shown an automobile door, an upholstered part for covering the inside of the door and separable fastener means for securing the upholstered part to the door.

45 Heretofore the fastener elements have been rigidly secured to the frame of the door and to the upholstered part and some difficulty has been encountered in registering the fastener elements on the upholstered part with the fastener elements on the door frame.

50 To remedy this difficulty, I have provided, as illustrated, a plurality of shiftable studs located on one of the parts for engagement

with rigid socket means on the other part, thereby permitting perfect alignment of any of the studs with their cooperating sockets. 55 Thus the upholstered part may be secured to the door without difficulty and the edges of the upholstered part may be properly "lined up" with the edges of the door.

Referring now to Figs. 2, 3, 4 and 5, I 60 have shown an upholstered part which includes a backing 1 of relatively stiff material such as cardboard or the like, constituting a form which is provided with a plurality of holes 2 adjacent the edges thereof, and a plurality of shiftable studs co-operating with the holes 2. These studs are secured to the front face of the backing by a casing or attaching plate 3, and their heads are presented, through the holes 2, at the 65 opposite face thereof for cooperation with the stud-receiving means on the part to be upholstered.

In the form of my invention illustrated, by Figs. 1 through 6 each stud is provided 75 with an attaching plate, herein serving as a base loosely carrying the stud to permit shifting of the stud without corresponding shifting of the base. Two types of attaching plates are shown, each providing portions overlying and underlying the base flange of the stud.

Each stud is assembled with its attaching plate 3 at the factory, thereby to provide a stud unit which may be easily, quickly and accurately secured in the proper relation to a hole 2 in the backing of the upholstered part, by the use of proper dies for registry with the aperture and for holding the stud-attaching plate. The stud and attaching plate, I term collectively a stud unit.

The socket-engaging part of the stud unit is pressed from a single sheet of metal and is provided with a base flange 4, a shank portion 5, a head 6 and a neck 7 between the head and shank portion. The head, neck and shank portions are rendered resiliently contractible by a plurality of slots, herein shown as three, which preferably, as illustrated, extend to or slightly into the base of 90 the stud.

In the form of my invention shown in Figs. 3, 4, 5 and 6, the attaching casing or plate 3, which is pressed from a single sheet

of metal, presents a smooth bottom, an up-standing peripheral wall 8, a plurality of stud-retaining prongs 9 and attaching prongs 10 extending from the wall 8.

5 The stud may be assembled with the attaching plate by placing the base portion 4 of the stud into the recess provided by the upstanding wall 8 and then bending inwardly the stud-retaining prongs 9 until they 10 overlie the base of the stud, thereby holding the stud and attaching plate in assembled relation even prior to assembly with the backing, as best shown in Fig. 6.

As illustrated, the diameter of the base 15 portion 4 of the stud is less than the diameter of the attaching plate and the short prongs 9 do not extend to the shank portion 5 of the stud, thus permitting free lateral movement of the stud in any direction relative to the attaching plate.

20 Assembly of a stud with the backing 1 is effected preferably by dies (not shown) which align the attaching plate 3 with a hole in the backing and force the attaching 25 prongs 10 through the backing, where they are upset against the opposite face thereof, as best shown in Figs. 4 and 5.

The holes in the backing are somewhat 30 larger in diameter than the diameters of the shanks of the studs, thereby permitting sufficient free movement of the studs in any lateral direction relative to the backing to compensate for variation in the exact positioning of the stud-receiving apertures in the 35 door or other part to be covered by the upholstery installation.

The advantages of securing the stud to the front face of the backing instead of the back face are, firstly, that for the same projection 40 beyond the face of the installation, a shank portion 5 of considerably greater length may be used, thereby affording an opportunity for greater resiliency of the head of the stud, and, secondly, that the strain exerted on the 45 stud when it is separated from the socket to which it is secured, is taken by a considerable area of the backing and not by the prongs, as when the studs are secured to the back face of the backing. The smooth bottoms of 50 the studs, as shown in Figs. 3, 4, 5 and 6, promote smoothness of the covering 11 in the completed upholstery installation and permit the studs to be pressed into engagement with their sockets without injury to the covering 55 11, which conceals the studs from view.

When the studs are all secured to the backing 1, a padding 12 is placed over the backing to improve the appearance of the edge of the upholstered part and to provide a surface which is generally in line with the bottoms of the stud-attaching bases. Thus the covering 11 of cloth, leather or the like is stretched smoothly and evenly over the outer face of the backing and its edges are secured 60 to the inner face of the backing, thereby pro-

viding a neat upholstered finish covering the outer face of the backing.

The door 13, to which the upholstered part is secured, may be, as illustrated, formed of sheet metal and preferably presents at the 70 inner face thereof, adjacent the periphery, a metal frame 14 having a plurality of stud-receiving apertures 15 punched or drilled therethrough for reception of the heads of the studs located on the upholstered part. 75

The upholstered part may be applied to the door by pressing the heads 6 of the studs into the stud-receiving apertures, thereby holding the upholstered part tightly against the frame of the door. 80

If any stud does not register with its co-operating aperture in the frame, the stud may be shifted, by the use of a suitable tool inserted between the frame and the upholstered part, until it is in proper position to 85 be pressed into engagement with its co-operating aperture. Thus adjustability of the positions of the studs is particularly important where the sheet metal door covering 90 and the flanges providing the frame 14 are integral, the flanges bent over after the holes therein are punched. In such case, because of unequal stretching of the metal, the stud-receiving apertures are exceedingly likely to 95 be slightly out of their desired positions. However, the capability of the studs to shift is desirable, even when the door frame or other carrying part is drilled in a jig, and the backing punched in a similar jig. Where the upholstered part is used as a covering for 100 something other than a door, and particularly where it is used with a heavily padded covering, the shiftability of the studs becomes even more essential. 105

Referring now to the form of my invention, illustrated in Figs. 7 through 9, I have shown a fastener unit including a stud substantially as shown and described in connection with the embodiment of my invention by Figs. 1 through 6. 110

The attaching part 17, in this instance, has its body seated against the backing, the body apertured to permit passage of the stud therethrough, while providing substantial clearance to permit lateral shifting of the 115 stud. The metal surrounding the aperture is thrown up to provide a tubular rivet 18 which may be clenched against the opposite face of the backing. The rivet may or may not be of a character to punch its own hole 120 in the backing, but preferably fits the hole relatively closely so that the backing is strongly reinforced, as by a grommet.

The stud is held in assembly with the stud-attaching part by having the base thereof seat against a flange of the attaching part which extends inwardly from one edge of the wall 19, the base of the stud being overlain at the other side by stud-retaining means herein shown as ears or prongs 20 125

which extend inwardly from the other edge of the wall 19. In the preferred embodiment shown in Figs. 7, 8 and 9, the prongs 20 project from an upstanding peripheral wall surrounding the body of the attaching part 17, the edge of this wall, in conjunction with the padding 12 contributing to the smooth appearance of the covering 11, where it overlies the attaching part 17.

10 The prongs 20, bent over the base of the stud, prevent separation of the stud from the attaching plate during shipment, and before the covering 11 is applied to the upholstered part. They also take a part of the strain 15 when the stud is being pressed into its stud-receiving aperture.

Attachment of the upholstered part, having the form of stud units, shown by Figs. 7 through 9 with the frame is effected in the 20 same manner as described in relation to the form of my invention shown by Figs. 1 through 6.

While I have shown and described my invention in connection with application of an 25 upholstered part to the door of an automobile, it should be understood that upholstery may be applied in a similar manner to other surfaces where a neatly finished upholstered part is required. The illustrations of my 30 invention and the description thereof are merely for clarification and not for limitation, my invention being best defined in the appended claims.

I claim:

35 1. A fastener unit comprising, in combination, an attaching part, means integral with said attaching part for securing it to a suitable support and a laterally shiftable snap fastener part loosely assembled with 40 said attaching part, said snap fastener part being shiftable to a limited extent in any direction transverse to the axis of said casing.

2. A fastener unit comprising, in combination, a casing part, a shiftable snap fastener part assembled with said casing part, said snap fastener part being freely shiftable in any lateral direction relative to said casing part and attaching means extending 50 from one face of said casing part in a direction generally parallel with the axis thereof for securing said fastener unit to a support.

3. A stud unit including a socket-engaging stud part, an attaching part having 55 means for securing said stud unit to a support, means forming part of the stud unit for holding said socket-engaging stud part in assembled relation with said attaching part and means cooperating between the 60 socket-engaging stud part and the attaching part to permit free shifting of the socket-engaging stud part in any lateral direction relative to said attaching part.

4. A shiftable stud unit including a casing 65 part having means integral therewith for

securing the casing to a support and a stud part having a base portion of smaller diameter than the diameter of the casing part assembled within said casing part, said stud base being freely shiftable in any transverse 70 direction relative to the casing part.

5. A stud unit including a laterally shiftable stud part, an attaching part formed from a single piece of metal and having integral means for securing said stud unit to a 75 support and means forming part of said unit for retaining said parts in assembled relation while permitting shifting movement of said stud part in any lateral direction relative to said attaching part. 80

6. A shiftable stud unit including a casing part, a socket-engaging part assembled with said casing part, means forming part of the stud unit and permitting said socket-engaging part to be freely shiftable in any 85 transverse direction relative to said casing part and attaching means extending outwardly from said casing part in the same direction as said socket-engaging part for securing said casing part in a fixed relation 90 with a suitable support while the socket-engaging part may be adjusted laterally relative to the support.

7. A shiftable stud unit including a casing part having a rivet portion extending 95 from one face thereof to secure said casing part to a suitable support and a laterally shiftable stud part assembled with said casing part so as to be movable in any transverse direction relative to said casing part 100 and the support.

8. A fastener unit comprising, in combination, a casing part having a peripheral wall, a flange portion extending inwardly from one edge of said peripheral wall, a tubular rivet portion extending outwardly from said flange portion, a cooperating stud having a base portion located in the space provided by said peripheral wall and having one face thereof bearing against said flange portion and means extending from the other edge of said peripheral wall parallel with said flange portion, said means extending over the other face of said stud base to hold said stud in assembly with said 115 casing, said base portion being smaller in diameter than the space enclosed by said peripheral wall and thereby being shiftable in any lateral direction in said casing part, said stud having a head, neck and shank pressed 120 from said base and extending through said tubular rivet portion. 125

9. A stud unit comprising, in combination, a casing part and a stud part, said stud part having a head, a neck and a base, said 125 casing part having spaced means extending over both faces of said stud base to hold the stud part and the casing part in assembled relation, means provided by the stud unit to permit shifting of the stud part in any 130

lateral direction to the casing part and attaching means extending from the casing part to secure the stud unit to a suitable support.

- 5 10. A stud unit including a casing having a peripheral wall, a flange extending inwardly from said wall, a laterally shiftable stud having a base seated against said flange and a head and neck passing through an 10 opening in said flange, the opening being of larger diameter than said stud head, said base being smaller in diameter than the space enclosed by said peripheral wall, means forming part of the stud unit for securing it to a support and means extending inwardly from said peripheral wall over the opposite side of the base of the stud for holding it in assembly with said casing, the space between the edge of the base of the 15 stud and the inner face of the peripheral wall of the casing being of sufficient dimensions to permit free transverse shifting of 20

the base of the stud in all directions relative to the casing.

11. A fastener unit comprising, in combination, a casing part having a peripheral wall, a flange portion extending inwardly from one edge of said peripheral wall, a tubular rivet portion extending outwardly from said flange portion, a cooperating stud 25 having a base portion located in the space enclosed by said peripheral wall, said base portion having one face thereof bearing against said flange portion, means extending from the other edge of said peripheral 30 wall parallel with said flange portion, said means extending over the other face of said stud base portion to hold said stud in assembly with said casing part, and a head and neck portion of said stud extending 35 through said tubular rivet portion.

In testimony whereof, I have signed my name to this specification.

ROLLO F. WALTERS.

CERTIFICATE OF CORRECTION.

Patent No. 1,675,998.

Granted July 3, 1928, to

ROLLO F. WALTERS.

It is hereby certified that error appears in the printed specification of the above numbered patent requiring correction as follows: Page 1, line 103, strike out the words "casing or" and insert the same before the word "attaching" in the same line; page 3, lines 42 and 43, claim 1, strike out the word "casing" and insert instead "attaching part"; page 4, line 7, claim 10, after the word "said" insert the word "peripheral"; and that the said Letters Patent should be read with these corrections therein that the same may conform to the record of the case in the Patent Office.

Signed and sealed this 7th day of August, A. D. 1928.

M. J. Moore,
Acting Commissioner of Patents.

lateral direction to the casing part and attaching means extending from the casing part to secure the stud unit to a suitable support.

- 5 10. A stud unit including a casing having a peripheral wall, a flange extending inwardly from said wall, a laterally shiftable stud having a base seated against said flange and a head and neck passing through an 10 opening in said flange, the opening being of larger diameter than said stud head, said base being smaller in diameter than the space enclosed by said peripheral wall, means forming part of the stud unit for securing it to a support and means extending inwardly from said peripheral wall over the opposite side of the base of the stud for holding it in assembly with said casing, the space between the edge of the base of the 15 stud and the inner face of the peripheral wall of the casing being of sufficient dimensions to permit free transverse shifting of 20

the base of the stud in all directions relative to the casing.

11. A fastener unit comprising, in combination, a casing part having a peripheral wall, a flange portion extending inwardly from one edge of said peripheral wall, a tubular rivet portion extending outwardly from said flange portion, a cooperating stud 25 having a base portion located in the space enclosed by said peripheral wall, said base portion having one face thereof bearing against said flange portion, means extending from the other edge of said peripheral 30 wall parallel with said flange portion, said means extending over the other face of said stud base portion to hold said stud in assembly with said casing part, and a head and neck portion of said stud extending 35 through said tubular rivet portion.

In testimony whereof, I have signed my name to this specification.
